UNITED STATES PATENT OFFICE.

HENRY M. DARLING, OF SENECA FALLS, NEW YORK, ASSIGNOR TO
ADELBERT S. DAVIS, OF SAME PLACE.

CIRCULAR SAWING MACHINE.

SPECIFICATION forming part of Letters Patent No. 389,061, dated September 4, 1888.

Application filed February 24, 1888. Serial No. 265,150. (No model.)

To all whom it may concern:

Be it known that I, HENRY M. DARLING, of Seneca Falls, in the county of Seneca, in the State of New York, have invented new and 5 useful Improvements in Circular Sawing Machines, of which the following, taken in connection with the accompanying drawings, is a full, clear, and exact description.

This invention relates to an improvement in 10 circular sawing machines; and it consists in certain peculiarities of the construction and arrangement of the same, substantially as will be hereinafter more fully described and claimed.

In order to enable others skilled in the art 15 to which my invention pertains to make and use the same, I will now proceed to describe its construction and operation, referring to the accompanying drawings, in which—

Figure 1 is a front elevation of the machine. 20 Fig. 2 is an end elevation with the balance-wheel removed to better show the working mechanism. Fig. 3 is a top plan view with the table partly broken away; and Fig. 4 is a vertical longitudinal section through the saw-table, showing it arranged for use in grooving.

a represents the main frame of my machine, of any size, form, or material found most desirable, and provided on top with a frame, *a'*, and hinged at the back side is the table-top *a''*, 30 as shown. As will be seen in Fig. 3, this top is made in two parts, at the joint of which the saw is placed, and one of the parts, for convenience in removing and replacing the saw, is made readily adjustable to and from the other 35 by means of eccentric clamps *a³*, pivoted under one edge of the frame *a''* and engaging the beveled edge of the hinged portion *a'* of the top frame. In the front end of frame *a'* is an elevating screw, *b*, for elevating and lowering 40 the table for use in grooving, as will more fully appear hereinafter.

The saw-shaft *b'* is journaled transversely of the machine beneath the work-table, and is provided on its inner end with the circular 45 saw *b''* and on its outer end with a balance-wheel, *b³*, as illustrated. A pinion, *c*, on this shaft meshes with a gear, *c'*, on the shaft *c²*, which extends across the machine, and is provided on its end with a crank, *c³*, or equivalent means for applying power thereto. Power 50

may be applied to the outer end of either the saw-shaft *C* or shaft *c²*. Cast upon the inner side of the pinion *c* is a worm, *d*, and pivoted upon the saw-shaft adjacent to this is the adjustable feed-carrier *d'*, consisting of a frame 55 pivoted to swing upon the shaft and formed at each end with a concentric slot, *d²*, through which pass the securing bolts and screws *d³*, for securing this frame, if desired, at any point convenient for the work under operation. In 60 the upper part of the swinging frame are formed a pair of slots *e*, which are vertical to the main shaft, or, in other words, are parallel to a radius drawn from the shaft, and in these slots are adjustably secured by the bolts 65 *e'* the feeding-frame *e²*, which extends across over the table to a point at or nearly in line with the saw. This will be clearly understood by reference to the drawings, in which it is 70 fully illustrated. In this frame is journaled a shaft, *f*, on the inner end of which, in line with the saw-blade, is removably secured a toothed feeding-disk, *f'*, which may at any time be removed by removing a thumb-nut which secures it, in order to replace it with 75 another of different size. On the outer end of this shaft is a bevel-gear, *g*, which meshes with a similar gear, *g'*, on a shaft, *h*, held in offsets of the swing-frame *d'* and feed-frame *e²*, and has on its lower end a worm-gear, *h'*, which receives motion from the worm on the saw-shaft. 80 In operation, the material to be sawed is laid upon the table and the frames *d'* and *e²* are adjusted, so that the feed-disk rests just at the proper height to properly feed stuff of the desired thickness. In ordinary work it is not necessary to secure the bolts *d³*, thus leaving the frame *d'* free to adjust itself to accommodate different thicknesses of work. The feed-disk receives a slow motion from the saw-shaft 85 by means of the worm and the intermediate gears and shafting, and the teeth of the disk engage and feed the stuff through with great accuracy and speed.

It will be particularly noted that the feed is 90 derived from the saw-shaft, and that no matter what thickness of material is used in sawing the feed-disk always maintains the same position relative to the edge of the saw, because in adjusting the feed for different thick- 100

nesses the whole feed mechanism swings upon the saw-shaft, which is the saw center. Should the ordinary adjustment not be sufficient for very thin stuff, the feed frame is loosened and lowered in its parallel slots till the required point is reached. In this movement the bevel-gear g' slides readily on the shaft h , and no disarrangement of the parts occurs.

In Fig. 4 I have shown the machine as used for grooving. In this case the rip-saw is replaced by a grooving-saw of the requisite size and the table lifted at one end by the elevating-screw provided for the purpose till only so much of the saw-blade projects above the table as corresponds to the depth of the groove required. The feed devices are adjusted as before, and in this case I bring into play a small roller, m , secured on the end of a slotted arm, m' , adjustably secured to the feed-frame. This roller is adjusted to bear upon the work in rear of the saw and prevent any jumping of the work while under operation. The machine is intended more particularly for hand or foot power, but may of course be run by any motor desired.

A gage-bar, n , extended across the table and adjustable to and from the saw, is used to guide the work and gage its cut.

Having thus fully described my invention, what I claim as new, and desire to secure by Letters Patent, is—

1. The combination, with a frame pivoted on the saw-shaft journaled on the main frame, with concentric slots in its outer edges and set-screws passing through the slots and into the top or table of the frame, of a second frame secured to the first in parallel slots vertical to the saw-shaft, a shaft carrying a miter-gear journaled in said frame, an adjustable guide-roller, a feeding-disk, a vertically-adjustable top or table hinged to the main frame, a slitting saw mounted on the saw-shaft, and means for tilting the table, all substantially as described, and for the purpose set forth. 35

2. The combination, with the saw-shaft b' , 40 provided with a worm, d , of the frame d' , swinging on said shaft, the frame e' , secured thereto, and the feed-shaft f , feed-disk f' , gears $g\ g'$, shaft h , and worm-gear h' , all constructed and arranged for operation substantially as and 45 for the purpose set forth.

In testimony whereof I have hereunto signed my name, in the presence of two attesting witnesses, at Seneca Falls, in the county of Seneca, in the State of New York, this 16th day of February, 1888. 50

HENRY M. DARLING.
